UNITED STATES PATENT OFFICE.

GEORGE E. NUTTING AND JOSEPH C. GITHENS, OF NEW YORK, N. Y.,
ASSIGNORS TO A. C. RAND, OF SAME PLACE.

IMPROVEMENT IN ROCK-DRILLS.

Specification forming part of Letters Patent No. 140,637, dated July 8, 1873; application filed June 30, 1873.

To all whom it may concern:

Be it known that we, GEORGE E. NUTTING and JOSEPH C. GITHENS, of the city, county and State of New York, have invented a new and useful Improvement in Rock-Drill, of which the following is a specification:

Figure 1 is a longitudinal section of our improved drill. Fig. 2 is a detail section taken through the line *x x*, Fig. 1.

Similar letters of reference indicate corresponding parts.

Our invention has for its object to furnish an improved steam rock-drill, which shall be so constructed that the valve may be shifted at the proper time to cut off the steam, and at the same time admit the steam in front of the piston, so that it may cushion itself upon steam and diminish the jar or shock, and in which the piston may turn, and thus turn the drill as it makes its up stroke.

The invention consists in the combination, with the slide-valve of a steam rock-drill, of pistons so constructed as to exhaust the steam from the end parts of the steam-chest in front of said valve and pistons; in the combination, with the piston of a steam rock-drill, of a rotating device so constructed that it may be held to its work by friction, and may yield should the drill-bit be prevented from turning; in the loose ring and adjustable stationary friction-strap, and the pawl and ratchet, or equivalent, in combination with the piston of a rock-drill; and in an improved chuck for rock-drill bits, formed by dividing the hollow forward end of the piston-rod longitudinally into three or more parts, and contracting said parts to hold the drill-bit by a strap or clip, open upon one or both sides, as hereinafter fully described.

A is the steam-cylinder. B is the piston which moves up and down in the cylinder A, and the rod C, which passes out through a stuffing-box at the lower end of the cylinder A. To the lower end of the piston-rod C is secured by a suitable coupling, D, the drill-bit or cutting-tool E. F is the steam-chest, from the middle parts of which the ports G lead into the cylinder A at or near its ends. H is the port through which the steam exhausts. I is the valve, by the movements of

which the ports are opened and closed. J is the valve-stem, which passes through and slides in the valve I, and the end parts of which slide in stuffing-boxes in the ends of the steam-chest F. To the end parts of the valve-stem J are rigidly attached two disks, K, at a distance apart equal to the distance required for the throw of the valve I, and an additional thirty-second of an inch, more or less. Upon the stem J, upon each side of the valve I, are placed pistons, L, of such a size as to work steam-tight in the end parts of the steam-chest F, and of such a length as to give the valve I and two pistons K a play of about a thirty-second of an inch upon the stem J, between the disks K. The diameter of the disks K is made enough less than the diameter of the end parts of the valve-chest to allow the steam to pass the said disks freely. In the end parts of the pistons L are formed ring-grooves M, from which holes m' lead out through the ends of said pistons, as shown in Fig. 1. N are exhaust-ports leading out from the end parts of the steam-chest to the open air. By this construction, as the piston B comes into the position shown in Fig. 1, the lower port O is uncovered and the steam passes through it into the lower end of the steam-chest F, below the lower disk K. As the steam enters the lower part of the steam-chest F it forces the disks K, pistons L, valve I, and valve-stem J upward until the upper disk K strikes its stop and stops the forward movement of the stem J and disks K. The steam now passes around the edge of the lower disk K and forces the pistons L and valve I upward until stopped by the upper disk K. This movement allows the steam in the end part of the steam-chest F to exhaust through the the exhaust N. The exhausts N are so arranged as not to be fully closed until the valve-pistons and disks have nearly completed their stroke. By this construction the valve I and its attachments and the piston B will always move in the same direction, which lessens the jar, and consequently the wear, of the mechanism. It will be observed that by arranging the exhausts O the piston B and valve I and its attachments may be cushioned with steam at one

or both ends of their stroke, and to any desired extent. P is an angular spiral or twisted rod, which is swiveled to the upper head of the cylinder A, and which passes through a guide-nut, Q, secured in the upper end of the piston B. To the outer end of the rod P is attached a ratchet-wheel, R, upon the teeth of which the pawl S takes hold. The pawl S is placed in a ring, T, and is held forward against the ratchet-wheel R by a spring. The ring T surrounds the ratchet-wheel R, and is in turn surrounded by the friction-strap U, which is rigidly connected with the cylinder-head. The strap U is open, and its ends are connected with each other by a bolt, so that it may be readily adjusted to take up the wear or to regulate the friction. The pawl and ratchet may be substituted by a simple friction device, so arranged as to rotate the piston B as it rises, but to allow said piston to descend without turning. The lower end of the piston-rod C is made hollow to receive the drill-bit E, and is slotted longitudinally to divide it into three or more parts, which parts are pressed together to clasp the drill-bit E by a strap or clip, W, which is made open upon one or both sides, and the ends of which are secured by bolts, so that the drill-bit E may be securely held and may be conveniently detached when desired.

Heretofore chucks for rock-drills have been made with two longitudinal slots extending the length of the bore, but the continual percussion and strains upon the drill-bar wear an oblong hole in the end of the chuck, causing much trouble and uncertainty in the direction of the blow given.

By dividing the chuck into three longitudinal slots, and surrounding it with a strap, we

bring the pressure to bear equally from all directions, the bar is kept straight, and any wear taken up by tightening the strap.

Having thus described our invention, we claim as new and desire to secure by Letters Patent—

1. The combination, with the valve I, of pistons L and port N, constructed substantially as described, so as to exhaust the steam from the end of the steam-chest F into the main exhaust, or directly to the atmosphere, as shown.

2. The combination, with the piston of a steam rock-drill, of a rotating device, substantially such as is herein described, so that it may be held to its work by friction, and may yield should the drill-bit be prevented from turning.

3. The loose ring and adjustable stationary friction-strap and pawl and ratchet, or equivalent, with the piston of a rock-drill, substantially as herein shown and described.

4. An improved chuck for rock-drill bits, formed by dividing the hollow forward end of the piston-rod C longitudinally into three or more parts, and contracting said parts to hold the drill-bit by a strap or clip, open upon one or both sides, substantially as herein shown and described.

5. The valve mechanism, substantially as described, consisting of the piston-valves L, disks K, valve I, and ports N, as and for the purposes specified.
